UNITED STATES PATENT OFFICE.

HANS HELLAND AND FRANTZ MATZOW, OF HOUSTON, TEXAS.

STATION-INDICATOR.

SPECIFICATION forming part of Letters Patent No. 391,529, dated October 23, 1888.

Application filed February 7, 1888. Serial No. 263,255. (No model.)

To all whom it may concern:

Be it known that we, HANS HELLAND and FRANTZ MATZOW, of Houston, in the county of Harris and State of Texas, have invented a new and Improved Station-Indicator, of which the following is a full, clear, and exact description.

Our invention relates to an improvement in station-indicators, and has for its object to provide an apparatus which will indicate to the passengers of railway or street cars when the car is approaching, standing at, or leaving a station, the station or street name, distance from the last station passed or to the next station, or any point upon the line that may be desired, and wherein all of the above data may be displayed simultaneously or any one or more items.

The invention consists in the construction and combination of the several parts, as will be hereinafter fully set forth, and pointed out in the claims.

Reference is to be had to the accompanying drawings, forming a part of this specification, in which similar letters and figures of reference indicate corresponding parts in all the views.

Figure 1 is a transverse vertical section through a car having our device attached. Fig. 2 is a partial longitudinal section through the same. Figs. 3, 4, 5, and 6 are detail views. Fig. 7 is a front elevation of the body of the indicator, and Fig. 8 is a longitudinal vertical section through the same. Figs. 9 and 10 are vertical sections through the body of the indicator, illustrating a modification thereof for circuitous routes.

It is the prime object of this invention to provide a device which will be of great benefit to the traveling public, especially to foreigners or people hard of hearing, for the brakeman's "calling out" is often entirely inadequate to convey the desired information.

Referring to the drawings, upon the axle 10 of the car-wheel a sprocket-wheel or grooved pulley, 11, is keyed or otherwise secured, which wheel is connected by an endless chain, 12, with another sprocket-wheel or grooved pulley, 13, journaled between the car-beams or the floor-beams, as is best adapted to the construction of the car. The bearings of the wheel 13 are movable, and consist of a suit-

able arm, 14, hinged to a metal support, as shown in Fig. 4, which hinged arm, upon either side near the top, is united to the support by strong spiral or coiled springs 15, 55 the object of the said springs being to neutralize the springs upon the truck. As shown in Fig. 3, the journal of the wheel 13 is connected by a universal joint with a short horizontal shaft, 16, and a second horizontal shaft, 60 17, carrying a worm, 18, is universally connected to the aforesaid shaft, the latter shaft, 17, being held to turn in suitable bearings. The worm 18 diminishes the motion of the wheel or pulley 13 and communicates the reduced motion to a worm-gear, 19, secured at the lower end of a vertical shaft, 20. The shaft 20 is projected through the car-floor along the inside wall, preferably between said wall, the closet, and door-frame, to a point in 70 the clear story above the bell-cord aperture. The upper end of the shaft 20 is provided with a worm, 21, to further diminish the motion from the sprocket 13, which worm meshes with a gear, 22, keyed to a two-part horizontal shaft, 23, as illustrated in Fig. 8. The two-part shaft extends through the casing 24 of the indicator proper and is journaled in brackets 25 and 26, the brackets and casing being both secured to the wall of the car. The 80 preferred position of the casing, as indicated in Fig. 1, is in the clear story at one end of the car. The section *a* of the two-part shaft carries the worm gear-wheel 22 at its outer end, and within the casing is provided with a 85 reduced rectangular inner end, over which the hub of a gear-wheel, 27, is slid and secured. The abutting end of the inner section *a* is also squared and provided with a socket adapted to receive the reduced end of section *a*, the 90 aforesaid hub of gear 27 constituting a sleeve for the joint and uniting the two sections when in the position illustrated in Fig. 8. The section *a* of the two-part shaft passes through and is secured to a roller, 28, which roller extends longitudinally of the frame at the bottom. The said shaft-section, projecting beyond the rear end of the roller, is projected beyond its bearing through the case and provided with a hand-wheel or button, 29.

In the upper end of the brackets 25 and 26 a second horizontal shaft, 30, is journaled par-

allel with the lower shaft-section *a* and carrying a roller, 31, similar in length to the roller 28. That end of the shaft passing beyond the bracket 26 projects through the casing, and to the extremity a hand-wheel or button, 32, is attached, aligning the wheel 29. Upon the opposite end of the shaft 30, which projects beyond the bracket 25 and within the casing, a gear-wheel, 33, is keyed, which gear is adapted, under circumstances hereinafter explained, to mesh with the under gear, 27. A strip or curtain, 34, of fabric of suitable width and a length adapted to the purpose, is attached at its ends to the upper and lower rolls, respectively, and wrapped upon said rolls in such manner as that a smooth unbroken outer face will be presented, as shown in Fig. 8.

Near the longitudinal edges of the curtain, at suitable distances apart, figures are produced upon the outer face, and between said figures the name of a station, the figure upon one side indicating the distance to the next station and the figure upon the opposite side the distance from the last or from the first station on the road. Motion is communicated from one roller to the other and the curtain compelled to wind smoothly thereon by means of endless elastic bands 35, embracing the curtain and both rollers near the end, as illustrated in Fig. 8. Upon the curtain, also, between the figures and the name of the station, the fractions of a mile may be indicated, as at *d* in Fig. 7. The front of the casing is provided with an opening to display the said figures and station-name, and above the same with a central slot, 36, and at each side of the slot with an aperture numbered, respectively, 37 and 38.

To the rear of the frontispiece covering the slot 36 and aperture 37 and 38 a longitudinal strip, 39, is held to slide, manipulated by a button, 40, projecting through the slot 36. Upon the outer face of the sliding strip, at one end, the words "To" and "From" are produced, and at the other end the same words reversed. Thus when the word "From" is opposite one aperture the word "To" appears at the other, and vice versa. These words refer to the numbers below them—as, for instance, if the next station were Newark and the figure 10 were below the word "From," it would signify that the train at that time was ten miles from the last station passed or indicated, and the number 14 being under the word "To" would indicate that the distance from that point to Newark was fourteen miles. Within one margin of the main opening a pointer, 41, is produced, in front of which the fractional indications pass, and when the mark indicating a mile comes opposite this finger the numbers at each side of the station-name change, the same or the next station, as the case may be, appearing.

In order to reverse or throw the gearing out so that the rolls may be turned by hand, a shifting device is employed. This shifting device consists of a substantially U-shaped

lever, 42, fulcrumed in the bracket 25, one member, 43, of which extends downward parallel with the front of the casing and is provided with a shanked button, 44, which button, passing through a segmental slot, 45, in the casing, is free to move in the same. The other member, 46, of the shifting-lever is provided with a bifurcated extremity, which, spanning the hub of the gear 27, is secured thereto, as shown in Fig. 5. When the gearing is meshed, as shown, the under roll is revolved and the curtain wound thereon from the top roll. To reverse, the shifting-lever is carried to the outer end of the segmental slot 45, which motion causes the gear 27 to slide upon the shaft-section *a*, and thereby uncouple the sections *a* and *a* of the two-part shaft 23, and the gear 27 to mesh with the gear 33, whereby motion is communicated direct to the upper roller. When from any cause the curtain is to be shifted, the shifting-lever is carried to the center of the segmental slot, which motion uncouples the two-part shaft, yet does not cause any of the gears to mesh, whereupon the rolls may be manipulated by means of the buttons attached to their shafts.

When the cars are run in a circuit or belt route, the station-name belt will be an endless one, as illustrated in Fig. 9, in which 28 and 31 indicate the rollers, and above said main rollers friction felt or rubber covered rollers *a* are journaled, and between the said friction and main rollers the apron or name-belt passes. To the rear of the main rollers, at top and bottom, two horizontal series of smaller rollers, *b* and *b'*, are journaled in plates *d* and *d'*, which plates are attached to the brackets of the indicator, as shown in Fig. 6. The small rollers *b* have upon one side a small rubber cylinder, *b*², acting as a friction-roller, which is given motion by the flanges of the main rollers. The rollers *b'* run loosely in the direction with the canvas, and are provided with loose friction-wheels *b*³, adapted to turn in opposite direction to the said rollers *b'* in order to transfer motion to the rollers *b*. The lower journal-bearings are stationary, and the upper one is movable in slots *e*, and adapted to be secured by a set-screw to suit the length of the belt or apron. The friction-wheels *b*² and *b*³ prevent stretching of the canvas, and in short routes may be dispensed with and the rollers *b* *b'* run loosely.

Another modification is illustrated in Fig. 10, which is only practical on cars run in one direction. The rubber belts or bands 35 do not surround other rolls than the main ones 28 and 31, and in this instance are applied on the rolls under the curtain, and preferably made to run in a spur in the said rollers. If found desirable, instead of the rubber band or belt, a pinion intervening the main rollers may be employed, engaging suitable gear upon the rolls.

In Fig. 10 a reservoir, 51, is placed to the rear of the main rollers, provided with a slot, 52, in its front face at the bottom and top, the curtain passing from the rollers through said

slots and into the reservoir, where it falls from the top downward in regular folds, the curtain being drawn from the bottom of the reservoir.

5 It will be observed that whenever a division-line giving distance passes the hand or pointer 41 the car is that distance from the last station—that is, the distance indicated to the left below "From," the number to the left below 10 "To," giving the distance to the next station. The indicator by containing an additional row of numbers would give distances from any one point desired—for instance, terminal stations.

Having thus fully described our invention, 15 we claim as new and desire to secure by Letters Patent—

1. The combination, with a two-part shaft, one section being provided with an actuating-gear and a roller mounted upon the other, a 20 toothed sleeve uniting said gear, and a shifting device connected with said sleeve, of a shaft parallel with and above the two-part shaft, provided with a gear adapted to mesh with the sleeve, a roller mounted upon the upper shaft, a curtain carried by said rollers and endless belts passing around the rollers, and curtains, substantially as shown and described. 25

2. The combination, with a two-part shaft, the outer section provided with an actuating-gear, a roller mounted upon the inner section, a gear sliding on the outer section and coupling the said sections, and a shifting device attached to said coupling-gear, of a shaft parallel with and above the two-part 30 shaft, provided with a gear adapted to mesh with the coupling-gear, a roller mounted upon said upper shaft, an indicating-curtain carried by said rollers, and endless belts passing around the rollers and curtain, and means, 35 substantially as described, for actuating the two rollers from the two-part shaft, as and for the purpose specified.

3. The combination, with a two-part shaft, the outer section being provided with an actuating-gear, a roller mounted upon the inner section, a gear coupling the said sections and turning with the outer one, and a shifting device attached to said coupling-gear, of a shaft 40 parallel with and above the two-part shaft, provided with a gear adapted to mesh with the coupling-gear, a roller mounted upon said 45 upper shaft, a curtain carried by said rollers indicating the station and distances, a belt

passing around said rollers and curtain-knobs secured to one outer end of said shafts, and 55 means, substantially as described, for actuating the two-part shaft from the axle of a car, essentially as and for the purpose set forth.

4. The combination, with the axle of a car, a pulley upon the axle, a pulley beneath the car-body mounted in spring-actuated bearings, an endless belt connecting the two pulleys, a horizontal shaft universally connected with said latter pulley and carrying a worm, and a vertical shaft carrying a worm-gear at one end and 60 a worm at the other, of a two-part shaft actuated from said vertical shaft, a roller mounted upon the inner section of the two-part shaft, a second shaft parallel with the latter shaft, a roller mounted upon the second shaft, a curtain uniting the two rollers, an endless band passing over the rollers and curtain, and means, substantially as described, for actuating the rollers from the two-part shaft, essentially as and for the purpose specified. 65

5. The combination, with the roller-shaft of an indicator and the axle of a car, of a pulley mounted upon the axle, a pulley mounted in spring-actuated bearings beneath the car-body, a horizontal shaft universally connected 70 with said pulley carrying a worm at one end, and a vertical shaft provided with a gear at its lower end meshing with said worm, and having a worm at the upper end engaging a gear upon the roller-shaft, and combined to operate 75 substantially in the manner specified.

6. The combination, with the roller-shaft of an indicator and the axle of a car, of a pulley mounted upon the axle, a pulley mounted in spring-actuated bearings beneath the car-body, a horizontal shaft universally connected 80 with said pulley, and gearing uniting said shaft with the roller-shaft, substantially as specified.

7. The combination, in a station-indicator, 85 with the parallel rollers 31 28 and the endless band 35, passing around them, of the rollers above and below the rollers 31 28, and an indicating-curtain, 34, passing between each pair of rollers and along the front side of the 90 band 35, substantially as set forth.

HANS HELLAND.
FRANTZ MATZOW.
